UNITED STATES PATENT OFFICE.

LYLE STOCKTON ABBOTT, OF CHICAGO, ILLINOIS.

FIRE ARCH FOR FURNACES.

Application filed April 4, 1927. Serial No. 180,913.

My invention relates to fire arches for furnaces particularly the character wherein a plurality of refractory tile or fire bricks are supported by arch bars in such a manner as to form an arch having the lower portion thereof where it is exposed to the direct heat within the furnace composed entirely of fire brick and in which the supporting means for the fire brick is protected by the brick themselves.

It is a purpose of this invention to provide an arch of this character which shall be composed of very few parts and yet which will retain the desired amount of flexibility to enable it to expand and contract and adjust itself to the changes in temperature undergone in use with the furnace.

It is another object of this invention to provide an arch of this character with novel means for permitting the refractory elements and the supporting bars to adjust themselves relative to each other in order to take care of the difference in expansion and contraction between the supporting bars and the refractory material without subjecting either of them to any undue strain because of this difference.

In constructing fire arches for furnaces it is always necessary that the supporting beams and hanger bars for the tile be protected from the direct heat of the furnace and this makes it necessary to provide tile of such a character that they will close the space beneath the hanger bars and the supporting beams. But, it is also necessary in an arch of this character to provide means for taking care of the expansion and contraction of the refractory tile and of the supporting means so that the expansion of the various elements that make up the arch will not cause it to bind and subject any of the refractory tile to a very great pressure since such a pressure would result in the destruction of the tile which have very little resistance to compressive pressure. It is necessary therefore to so support the tile members within the arch that they may expand in any direction within limits and in this way adjust themselves to the various temperatures of the furnace.

It is a purpose of this invention to provide supporting means for the tile members which will permit the adjustment without in any way detracting from the strength of the arch from a mechanical standpoint and without leaving openings between the refractory ele-

ments through which the heat might attack the supporting means.

Other objects and advantages of the invention will appear as the description proceeds when taken in connection with the accompanying drawing. However, I wish it to be distinctly understood that I do not intend to limit myself to the exact details shown and described, but that I intend to avail myself of all modifications as would occur to one skilled in this art and as fall within the scope of the claims.

In the drawings:

Fig. 1 is a plan view of a portion of a furnace arch constructed in accordance with my invention;

Fig. 2 is a side view of the portion of the arch shown in Fig. 1;

Fig. 3 is a side view of the arch taken at right angles to Fig. 2;

Fig. 4 is a perspective view of one of the refractory tile members used in the arch; and

Fig. 5 is a perspective view of the other refractory tile member used.

Referring now in detail to the drawings, the arch is supported by means of a plurality of beams 10 and 11 which extend across the furnace and are secured in any suitable manner to the side walls 12 thereof. These supporting members are each made up of a plurality of channel bars 13 and 14 having the flanges thereof facing each other and being spaced apart by means of the spacing elements 15 and secured together by means of the bolts 16. Suspended from these supporting beams by means of the suspension members 17 are a plurality of arch bars 18. The suspension members 17 as shown in Figs. 2 and 3 have T-shaped heads thereon with the horizontal extending bars 19 and 20 resting upon the lower flanges of the channel beams and these bars 19 and 20 are rounded on their lower surface as shown at 21 in Fig. 3 to permit a slight rocking movement of the supporting members 17 relative to the flanges of the channel beams for a purpose which will presently appear. The supporting elements 17 as shown clearly in Fig. 3 are forked at their lower ends to receive the arch bars 18 which are provided adjacent their upper edges with the enlarged portions 24 over which the legs 22 and 23 of the members 17 fit and pivoted thereto by means of the bolts 25.

The arch bars 18 which are preferably

cast in one piece are enlarged at their upper and lower edges to reenforce the same and are provided at spaced intervals throughout their length with integral projections 26 and 27 extending from opposite sides thereof slightly above the enlarged door reenforcing edge. These projections 26 and 27 are substantially semi-cylindrical in cross section to provide a rounded upper surface upon which the refractory tile members 28 having the oval openings 29 therethrough may be supported. Refractory members 28 as shown clearly in Fig. 5 are recessed on opposite sides adjacent the top end thereof as at 31 and 32 and the opening 29 extends transversely through the thinner upper portion provided by the recesses 31 and 32. This opening as hereinbefore stated is oval in shape being elongated longitudinally horizontally of the block to provide for limited movement relative to the bars 26 and 27 in order to permit for adjustment of these blocks upon expansion of the arch relative to the arch bars 18. This is made necessary because of the fact that the expansion per unit length for a definite change in temperature is not the same for the cast bar 18 as it is for the refractory tile members. As shown by Fig. 3 each one of the bars 18 carries a row of the tile members 28 on each side thereof by means of the horizontal projections 26 and 27, the recessed portions 31 and 32 permitting the members 28 to come together beneath the bars 18 so as to cut them off from any direct attack of the hot gases within the furnace. The outside recess faces of the members 28 form seats for the projections 34 and 35 on the blocks 33 so as to support them between the rows of refractory members 28 carried by the bars 18 and thus form a complete closed arch for the furnace. Thus by suspending the requisite number of the bars 18 from the channel members and in turn supporting the refractory tile 28 from the bars 18 and filling in the spaces between the tile 28 with the tile 33, the furnace arch may be built up across the chamber. Side walls of the furnace are preferably provided with a shoulder 36 over which the end tile members 28 will project and any suitable resilient packing 37, such as asbestos or mineral wool, may be provided to close the space between the side walls and the arch and permit expansion and contraction at this point.

By the provision of the rounded lower faces on the T-shaped member made of the suspension members 17, these members may adjust themselves slightly with respect to the channel beams when the refractory tile members are expanded longitudinally of the channel beams under increase of the temperature in the furnace and since the

heads of the members 17 are free to slide longitudinally of the channel beams, they will readily adjust themselves so as to prevent any undue strain on the tile due to this expansion. The expansion longitudinally of the arch bars 18 is also taken care of by means of the elongated holes in the refractory tile supported on members 26 and 27 which permit the tile 28 to have a slight movement longitudinally of the bars 18 to take care of the difference in the expansion between the metallic bars and the refractory tile.

From the foregoing description it will be seen that I have provided a furnace arch which is constructed of a relatively few simple parts easily assembled or disassembled for the purpose of replacement and which is capable of adjusting itself under the changes in temperature encountered in the surface in a furnace and the danger of breaking the refractory tile. Also, the tile members which are used in this structure are so constructed that there are no sharp projecting portions which are liable to be broken off in handling or making the tile since there are no reentrant angles to cause difficulty in molding the tile and firing them.

Furthermore, by the provision of the particular type of arch bar and the means for supporting the tile thereon, the bars in the upper portions of the refractory tile are exposed so that the air may have ready access thereto and maintain them comparatively cool, which prevents deterioration of the arch bar and also lessens the liability of any breakage in the structure.

From the above description, it is thought the construction and advantages of my device will be clearly apparent to those skilled in this art.

Having thus described my invention, what I desire to claim and secure by United States Letters Patent is:

1. In a furnace arch, the combination of an arch bar having a row of longitudinally spaced horizontally extending projections on each side thereof, each of said rows of projections supporting a row of refractory tile thereon, the tile in said rows having inwardly offset portions extending from the top thereof below the lower edge of said bar, and having openings therethrough receiving said projections, the adjacent faces of said rows of tile being in contact below said bar.

2. In a furnace arch the combination of an arch bar having a row of longitudinally spaced horizontally extending projections on each side thereof, each of said rows of projections supporting a row of refractory tile thereon, the tile in said rows having openings therethrough receiving said projections, said openings being larger horizontally in a direction lengthwise of said bar.

than said projections to permit limited longitudinal adjustment of said tile on said bar.

3. In a furnace arch the combination of 5 an arch bar having a row of longitudinally spaced horizontally extending projections on each side thereof, each of said rows of 10 projections supporting a row of refractory tile thereon, the tile in said rows having 15 openings therethrough receiving said projections, said projections having rounded 20 upper surfaces engaging the tile.

4. In a furnace arch, the combination of 15 a plurality of spaced parallel arch bars each having a row of longitudinally spaced horizontally extending projections on each side thereof, each of said rows of projections supporting a row of refractory tile thereon, the tile in said rows having inwardly offset portions 25 extending from the top thereof below the lower edge of said bar, the adjacent faces of said rows of tile being in contact below said bar, and rows of refractory tile between adjacent bars having projections 25 resting upon the shoulders formed by the offsets in the outer faces of the tile carried by said bars.

5. A furnace arch construction comprising a plurality of supporting beams adapted to be supported by the furnace walls, a plurality of arch bars pivotally and slidably supported by said beams, rows of horizontal projections on opposite sides of each of said bars, a row of refractory tile supported by each row of projections the tile 35 in said rows having a shoulder formed thereon adjacent the top thereof, and rows of refractory tile between the rows of tile carried by said projections having projections resting on said shoulders. 40

6. A furnace arch construction comprising a plurality of arch bars, means for supporting said arch bars in spaced relation, each of said bars having integral therewith longitudinally spaced horizontal projections 45 on opposite sides thereof, a tile carried by each of said projections and a plurality of tile connected and supported by the tile on the projections of adjacent arch bars.

In witness whereof, I hereunto subscribe 50 by name this 29th day of March, A. D., 1927.

LYLE STOCKTON ABBOTT.
